US00D856603S

(12) **United States Design Patent** (10) **Patent No.:** **US D856,603 S**
(45) **Date of Patent:** **** Aug. 13, 2019**

(54) **AUTOMATIC FEEDER FOR PETS**

(71) Applicant: **Young Jun Hong**, Goyang-si (KR)

(72) Inventor: **Young Jun Hong**, Goyang-si (KR)

(**) Term: **15 Years**

(21) Appl. No.: **29/638,603**

(22) Filed: **Feb. 28, 2018**

(30) **Foreign Application Priority Data**

Sep. 5, 2017 (KR) 30-2017-0041431

(51) **LOC (12) Cl.** **30-07**

(52) **U.S. Cl.**

USPC **D30/122**

(58) **Field of Classification Search**

USPC .... D30/121, 122, 129–133; 119/61.5, 51.01, 119/61.56, 51.03, 59, 62, 63, 51.5, 57.8, 119/74, 61.54, 61.55, 53, 53.5, 75, 56.2, 119/51.02, 51.11, 51.12, 57.1, 52.1, 515; 312/204; 248/151, 188; 108/156, 108/153.1–157; 220/23.87, 630, 737, 220/743, 9.4, 495.01, 574, 212, 255, 220/23.83; 206/515; D7/586, 543, D7/550.1, 587, 505, 584, 545, 500, D7/553.1–553.8, 546, 555, 556, 504, 565, D7/562, 602, 605, 312, 313, 320, 307, D7/306, 309, 354, 311, 399, 397, 323, D7/332, 331, 347, 346, 322, 318, 317, D7/316, 619.1; D9/429; 43/109; D22/122; 99/430, DIG. 15, 280, 285, 99/312; 222/209, 131, 363, 349, 517, 222/153.13, 401, 1, 146.5, 23, 54, 64, 51, 222/156, 399, 400.8; 219/438, 439, 441, 219/385, 386, 402, 407; 210/94, 184, 210/474, 477; D34/7–10, 1; D14/300, D14/301, 302, 308, 314, 356–359, 363, D14/370, 420, 421, 439, 172, 188, 203.1, D14/204, 214, 221, 242, 299, 168, 197, D14/205, 210; D15/122, 135; D18/50

(57) **CLAIM**

The ornamental design for an automatic feeder for pets, as shown and described.

DESCRIPTION

FIG. 1 is a top perspective view of an Automatic Feeder for Pets showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a side perspective view thereof; and,

FIG. 9 is a bottom perspective view thereof.
